UNITED STATES PATENT OFFICE

114,585

DESIGN FOR A PORTABLE PHOTOCOPYING
MACHINE

Robert H. Fullerton, St. Paul, Minn., assignor to
Fullerton, Incorporated, St. Paul, Minn., a cor-
poration of Minnesota

Application March 13, 1939, Serial No. 83,545

Term of patent 14 years

To all whom it may concern:

Be it known that I, Robert H. Fullerton, a citizen of the United States, residing at St. Paul, county of Ramsey, and State of Minnesota, have invented a new, original, and ornamental Design for a Portable Photocopying Machine, of which the following is a specification, reference being had to the accompanying drawings, forming part thereof.

Figure 1 is a perspective view of my portable photocopying machine in closed position, showing my new design.

Figure 2 is a similar view of my machine in partially open position.

Figure 3 is a perspective view of my portable photocopying machine in open position, showing my new design.

I claim:

The ornamental design for a portable photocopying machine, as shown.

ROBERT H. FULLERTON.
